UNITED STATES PATENT OFFICE

EVANS W. BUSKETT, OF JOPLIN, MISSOURI

APPARATUS FOR TREATING METALLIC ORES

Application filed January 27, 1930. Serial No. 423,686.

My invention relates to apparatus for treating ores containing relatively volatile metals and more particularly to apparatus including a blast furnace in which materials such as zinc ores are reduced, volatilized, and condensed.

The ores of iron, copper and lead usually are smelted in a blast furnace, and copper and lead ores often contain zinc, the major portion of which is volatilized and oxidized, and thus passes out of the furnace and is lost.

Numerous attempts have been made to smelt zinc ores in a blast furnace and to recover the zinc in metallic form, but up to the present time, the attempted processes have failed, largely because of the fact that the zinc passes through the means used for condensing the vapors thereof in the form of blue powder and zinc oxide, the reduction of which is prevented because of the presence of carbon dioxide. The zinc usually collected in such processes is in the form of blue powder which contains about ninety per cent zinc due to the dilution of the zinc vapors by an excess of nitrogen, carbon dioxide and sulphur dioxide gases.

The principal objects of my invention therefore, are to effect recovery of metals in metallic form, to minimize the effects of dioxides in the use of apparatus of the character referred to, to reduce oxides passed from a furnace in vapor form, to minimize the formation of oxides in vapors of metals, to interpose reducing agents in a stream of metallic vapors for reducing metal oxides and promoting recovery of metals in metallic form, and to minimize the loss of metals passing from apparatus of this character in vapor form.

Further particular objects of my invention are to effect reduction of dioxides for promoting reduction of metal oxides, to introduce a supplemental reducing agent into the reducing medium for intensifying the reducing action, to carry out a condensation step with the exclusion of air for minimizing formation of oxides, to pass vapors of ore reduction immediately to a reducing medium for minimizing formation of oxides prior to condensation of the vapors, to effect reaction

between a metal oxide and a heated carbonaceous condensing medium for reducing the oxide to form molten metal and carbon monoxide, and to effect formation of carbon monoxide and hydrogen to assist in the reducing action for minimizing losses of metals in vapor form.

In accomplishing these and other objects of the invention, I have provided improved apparatus, the preferred form of which is shown in the accompanying drawing, wherein the single figure is a central vertical section of the apparatus.

Referring in detail to the drawing:

1 designates a blast furnace including a vertical wall 2, and having a feed hopper 3 at its upper end projecting downwardly thereinto, normally closed by a preferably conical valve 4 extending upwardly into and through the hopper. The valve is connected to a stem 5 pivotally connected at its upper end to the inner end of a lever 6 pivotally supported at 7 intermediate its ends by a bracket 8. A weight 9 connected to the outer end of the lever is adapted to normally maintain the valve in closed position.

The lower portion of the furnace may be jacketed as at 10 by a water jacket preferably formed in sections and provided with tuyères or openings 11 for introduction of an air blast into the furnace. A well 12 may be formed in the base of the furnace and provided with an outlet opening or siphon tap 13. The well is adapted for the collection of lead when the apparatus is used for the reduction of ores such as zinc ore containing a substantial proportion of lead.

Located adjacent the furnace is a suitable number of condensers communicating therewith, one condenser 14 being shown in the drawing including a wall 15 parallel with and spaced from the wall 2 and an opposite wall 16 defining a chamber in the condenser.

The walls 2 and 15 are apertured and connected by a flue-like conduit 17 to form a throat 18 located in an intermediate position in said walls and adjacent the smelting zone, the throat being illustrated as inclined upwardly from the furnace toward the condenser.

The condenser 14 is divided by a vertical wall 19 extending across the same parallel with the walls 15 and 16 in the path of vapors moving from the furnace to the condenser. 5 The wall extends upwardly preferably to the top of the condenser chamber, which is closed as presently described, and the bottom of the wall terminates a substantial distance above the bottom or floor 20 of the condenser, 10 to form a substantially U-shaped conduit including legs or branches 21 and 22 communicating through the passage formed by the transverse conduit branch of the upright U at the bottom of the chamber. 15 A collecting basin including an outer wall 23 is formed at the bottom of the condenser, the wall 16 extending downwardly into the basin to form an air seal, the lower edge of the wall 16 being spaced from the floor of the 20 basin to provide a channel 24 for flow of liquid from the inner portion 25 of the basin through said wall to the outer portion 26. Material such as zinc recovered with the apparatus may be siphoned from the outer portion 26, as will 25 be apparent. The upper edge of the wall 23 is spaced substantially below the lower edge of the wall 19 to provide a liquid level in the chamber below the wall 19 and a lateral passage between the level of liquid and the lower 30 edge of the wall 19.

A body of carbonaceous material 27 is arranged in the condenser, this material being in any desired form such as coke or carbon. The portion of the carbonaceous material in 35 the leg 21 of the conduit adjacent the furnace preferably extends upwardly at least to the top of the throat 18. After the vapors and gases have passed through the body of carbonaceous material in the leg 21, lateral 40 passage, and leg 22 of the condenser, they are discharged from the condenser through a lateral outlet flue 28 communicating with the leg 22 and connected to a fan (not shown) for continuously drawing vapors laterally from 45 the smelting zone through the condenser and carrying away the remaining gases and vapors after the metal has been recovered therefrom.

The legs of the conduit are adapted to be 50 supplied with carbonaceous material through hoppers 29 normally closed by preferably conical valves 30 connected to stems 31, the hoppers and valves closing and sealing the top of the condenser chamber. The stems are 55 pivotally connected at their upper ends as at 32 to levers 33 pivotally supported intermediate their ends as at 35 by brackets 36. Weights 37 are connected to the outer ends 60 of the levers to normally maintain the valves in closed position and thus exclude air from the chamber.

It is desirable under some conditions to 65 supply steam to the condenser for the purpose of generating hydrogen and carbon monoxide gases, and for this purpose a pipe 38 extends

through one wall of the condenser below the throat as shown in the drawing. A spray head 39 may be carried by the inner end of the pipe 38, and the latter is connected to a suitable source of steam. 70

The operation of the apparatus is as follows:

The ore, fuel and fluxes are charged into the blast furnace, the fuel, for example coke, providing the heat and reducing agent for the 75 reducing action, as will be apparent. It may be considered that three separate zones are provided within the furnace, the top zone extending upwardly from the top of the throat 18 to the top of the material within the furnace, the central zone extending from the top of the throat 18 downwardly to the tuyères 11, and the bottom zone lying between the tuyères and the well 12. 80

In the action of the apparatus, substantially all of the reduction of the ore takes place in the central zone, there being practically no chemical reaction in the top zone. The bottom zone may be for the reception of slag or other materials from which any small lead content may be recovered in a fore hearth. The well 12 is employed when the ore contains a material percentage of lead, in which case the molten lead will collect from the matte and slag and may be removed through 95 the siphon tap 13 in the usual manner. 100

The zinc vapors pass immediately and partly in the form of zinc oxide from the central or smelting zone laterally into the condenser through the throat 18 and downwardly into the body of carbonaceous material which constitutes a combination condensing and reducing body. The products of combustion and other materials from the blast furnace maintain the body of carbonaceous 105 material at an elevated temperature, the temperature of the material adjacent the throat 18 being above the vaporizing point of the metal and sufficiently high for the reduction of the zinc oxide. 110

The oxygen of the compound combines with the surface material of the carbon to form carbon monoxide, and thus the zinc oxide is reduced and the zinc is condensed by passage over the less heated portions of the material in liquid form to collect in the basin 20 together with the condensates of pure zinc vapors which, of course, are not subjected to any reducing action in the carbonaceous material but are merely condensed therein. 115

The carbon monoxide formed in the reducing action referred to obviously has a strong affinity for oxygen and accordingly assists in the reducing action by breaking down some of the zinc oxide. The carbon dioxide in the products of combustion passing from the blast furnace, is reduced to carbon monoxide upon contact with the heated carbonaceous material, thus affording a second source of this gas to assist in the reduction of the zinc 120 125 130

oxide present in the vapors. The molten zinc collected in the basin may be drawn off in any desired manner, for example by siphoning from the outer portion of the basin.

5 The outer leg of the U-shaped conduit is provided with a considerable quantity of the carbonaceous material to condense and check the escape of zinc vapor from the flue 28. Ordinarily, the reduction and condensation 10 are substantially completely carried out before the residual gases reach the flue 28, and these gases together with a negligible percentage of uncondensed vapors of metals may be taken from the flue to the bag house or 15 any other suitable collector.

Should the amount of metallic vapor and metallic oxide escaping reduction and condensation be considered excessive, an auxiliary agent such as steam may be introduced 20 into the superheated upper portion of the material in the condenser through the pipe 38, to provide an excess of carbon monoxide, and hydrogen. The steam acting with the hot carbonaceous material, is decomposed to 25 form hydrogen and carbon monoxide gases, the latter therefore forming a third source of carbon monoxide gas to insure the completion of the process with the loss of negligible quantities of the metal through the flue 28, 30 and compensate for any abnormally rapid movement of the gases and vapors through the carbonaceous material.

The agent introduced through the pipe 38 may consist of any suitable substance such as 35 a gas or liquid adapted to act with materials in the conduit to promote reduction and condensation of the metals, and particularly to effect production of hydrogen to act as a reducing agent.

40 It is desirable to exclude oxygen from the condenser, and accordingly the valves 30 are adapted to seal the condenser from the atmosphere. These valves may be readily opened when it is desired to introduce fresh charges 45 of carbon into the condenser. Similarly, the valve 4 prevents the introduction of air into the condenser through the top of the blast furnace due to the stack or draft effect created by the fan associated with the flue 28. 50 The only air provided is that which is fed through the tuyères, and this air passes through the central or active zone of the blast furnace to continue the proper combustion of the fuel therein.

55 While I have described in detail the preferred form of my invention it is to be understood that the form of apparatus shown and described and the details of procedure may be varied without departing from the spirit 60 of the invention or the scope of the subjoined claims.

What I claim and desire to secure by Letters Patent is:

1. Apparatus of the character described including a chamber having an inlet for vola-

tized metal products, and including a branch leading downwardly from said inlet and an upwardly extending discharge branch, a collecting basin connecting said branches and having a lateral outlet at its bottom, and a reservoir exterior to the conduit communicating with the basin through the outlet thereof and including means for maintaining a liquid level in the basin below the top of the basin. 70

2. In apparatus for treating metallic ores, a condenser including a floor and parallel vertical walls forming a chamber and having respectively inlet and outlet openings spaced from said floor, a vertical partition parallel with said walls and having a lower edge spaced from the floor to form inlet and discharge portions of said chamber and a passage connecting the chamber portions, means sealing the upper ends of said chamber portions, means for maintaining level of liquid below said lower edge of the partition, and means for passing vaporous products including metallic vapors through said inlet chamber portion for movement through the passage and discharge portion. 80

3. In apparatus for treating metallic ores, a condenser having a liquid outlet adjacent said floor, and including a floor and parallel vertical walls forming a chamber and having respectively vapor inlet and outlet openings spaced from said floor, a vertical partition parallel with said walls and having a lower edge spaced from the floor to form inlet and discharge portions of said chamber and a passage connecting the chamber portions, means sealing the upper ends of said chamber portions, reducing means in said inlet chamber portion, and means including a nozzle located to discharge into the chamber for introducing a fluid treating agent into said reducing means. 95

4. A condenser for metallic vapors having a U-shaped channel forming an inlet branch having a vapor port and an outlet branch having a vapor port, and a transverse branch, said ports being spaced substantially above the transverse branch, said condenser having a liquid outlet at the bottom of said transverse branch, and means for maintaining a level of liquid in said transverse branch below the top thereof for movement of vapors through said transverse branch above the liquid. 110

5. Apparatus of the character described including a bottom wall, a front wall having an inlet for metallic vapors, a rear wall spaced from the front wall to define a condensing chamber and having an outlet for waste gases and a lower edge spaced from the bottom wall 115 to provide a liquid outlet, a reservoir communicating with the chamber through said liquid outlet and including a wall having an upper edge extending above the lower edge of the rear wall to maintain a liquid level in 125 120 125 129

the chamber, an intermediate wall in said chamber sealingly dividing the chamber into inlet and outlet branches and having a lower edge spaced substantially above the plane of the upper edge of said reservoir wall to provide a passage between the branches above the level of liquid in the chamber, and means including a nozzle located in the condensing chamber for discharging treating fluid into the chamber.

6. In apparatus of the character described, a metallic vapor condenser comprising walls forming a chamber having a lateral inlet for volatilized metal products and including a branch extending downwardly from said inlet for conducting volatilized products in a downward direction and an upwardly extending discharge branch having a vapor outlet, a collecting basin forming a vapor passage connecting the lower ends of said branches and provided with a liquid outlet, means for controlling movement of liquid from said liquid outlet to maintain a liquid level in the basin below the top of said passage for permitting vapors to pass over the liquid in the basin, and means in said downwardly extending branch for treating said products.

In testimony whereof I affix my signature.
